UNITED STATES PATENT OFFICE.

CHARLES W. SHIPPEE, OF MILFORD, MASSACHUSETTS.

WATERPROOF BOOT OR SHOE AND METHOD OF MAKING SAME.

SPECIFICATION forming part of Letters Patent No. 529,880, dated November 27, 1894.

Application filed June 2, 1894. Serial No. 513,281. (No model.)

To all whom it may concern:

Be it known that I, CHARLES W. SHIPPEE, of Milford, county of Worcester, State of Massachusetts, have invented an Improvement in 5 Waterproof Boots or Shoes and Methods of Making Same, of which the following description, in connection with the accompanying drawings, is a specification, like letters on the drawings representing like parts.

10 Difficulty is experienced in the use of ordinary india rubber or waterproof boots and shoes wherein the upper and its sole are integral or in one piece, by the rapid wearing out of the sole when subjected to but comparatively little hard usage, and attempts 15 have been made to strengthen india rubber boots and shoes by the addition thereto of an outer sole composed of leather.

In accordance with my invention, I have 20 aimed to produce an india rubber upper and outer sole integral therewith in such manner that it may be readily incorporated with a leather outer sole and a tap sole, and this may be done without subjecting the latter to 25 vulcanizing heat during the operation of making the shoe.

Figure 1, in section, represents the different pieces of which my improved shoe is composed, the same being slightly separated; 30 and Fig. 2 shows the same assembled in accordance with my invention.

Referring to the drawings, the upper *a* has integral with it a sole *b* and the interior of the shoe has an inner sole *c*.

35 The parts so far described are and may be common to any usual india rubber boot or shoe.

In the drawings, *d* represents a filling or intermediate sole which may be of leather or of 40 any other desired material, and *e*, a leather outer sole. I provide means for uniting the ordinary india rubber boot or shoe with these soles, and to do this I apply to the upper *a* stay strip *f*, composed of cloth coated with 45 rubber, of rubber alone, or any material which will vulcanize to the rubber upper, and I stick or apply the same to the india rubber of the uppers when in their green state, and I then apply in the space between the bottom

of the usual sole *b* of the rubber shoe and the 50 side of the filling or intermediate sole, a layer *g* of similar vulcanizable fabric, and for the best results said layer will extend entirely through between the soles *b* and *d*.

By the usual vulcanizing processes, I unite 55 the stay strip *f* and the layer *g* together, portions of the stay strip and layer, one or both, preferably both, being extended sufficiently to constitute a wrap or binding which is fitted about the outer edges of the filling or intermediate sole *d*, which is lasted in the usual manner in making leather boots or shoes, as represented in Fig. 2, and then the outer sole *e* is applied and the outer sole and the filling or intermediate sole are united by nails, 60 screws, pegs, or fastenings commonly employed to unite soles in the manufacture of leather boots and shoes.

It will be seen that the flaps, as I may denominate the stay strip, and the edge of the 70 layer *g*, constitute a sort of binding stay which is firmly secured between the two soles *d* and *e*, and in assembling the parts after the portions *a*—*b*, *f*—*g*, have been united by vulcanization, it is preferable to apply to the 75 filling or intermediate sole suitable liquid india rubber cement to further aid in uniting the same together.

Having described my invention, what I claim as new, and desire to secure by Letters 80 Patent, is—

1. A waterproof boot or shoe composed of an india rubber upper and integral sole, and having one edge of a stay strip vulcanized thereto, a filling or intermediate sole, and an 85 outer sole of leather, the said stay strip being bent about the edges of the filling or intermediate sole and placed between said sole and the outer sole, the outer sole and the filling or intermediate sole being united by fastenings extended thereinto, substantially as described.

2. A waterproof boot or shoe composed essentially of an india rubber upper having a sole integral therewith, a layer of vulcanizable fabric vulcanized to the said rubber sole and extended outwardly for some distance 90 beyond the edges thereof, a filling or inter-

mediate sole, and an outer sole of leather, the edges of the layer of fabric being folded about the edges of the filling or intermediate sole and between the said sole and the outer sole, and fastenings extended into and uniting the filling or intermediate sole and the outer sole, substantially as described.

In testimony whereof I have signed my name to this specification in the presence of two subscribing witnesses.

CHARLES W. SHIPPEE.
